(57) **CLAIM**

I claim the ornamental design for a depth adjustable edger,
as shown and described.

DESCRIPTION

FIG. 1 is a front perspective view of a shovel according to
the instant design;

FIG. 2 is a rear perspective view thereof;

FIG. 3 is a front elevational view thereof;

FIG. 4 is a side elevational view thereof as seen from the left
hand side of FIG. 3;

FIG. 5 is a rear elevational view thereof the adjustable
portion shown at a higher setting;

FIG. 6 is a side elevational view as seen from the right hand
side of FIG. 3;

FIG. 7 is a bottom plan view thereof; and,

FIG. 8 is a top plan view thereof.

The broken line showing of the handle is included for the
purpose of illustrating environment and forms no part of the
claimed design.
